UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,272,624.

Specification of Letters Patent.

Patented July 16, 1918.

Application filed March 21, 1917. Serial No. 156,294.

To all whom it may concern:

Be it known that I, ROY D. CONWAY, a citizen of the United States, residing at Chatham, county of Morris, and State of New Jersey, have invented certain new and useful Improvements in Telephone-Exchange Systems, of which the following is a full, clear, concise, and exact description.

This invention relates to telephone exchange systems, its object being the provision of improved signaling means for such systems.

In accordance with this invention, a link circuit, employed in interconnecting subscribers' lines for conversation, is provided with apparatus by means of which ringing on a called line starts almost immediately upon the connection of the link circuit therewith. The link circuit is also provided with motor mechanism, preferably in the form of a step-by-step actuated electromagnet, for controlling the period of ringing; that is, the duration of the ringing and silent intervals.

This invention, in one embodiment, is illustrated in the accompanying drawing, in which there are telephone lines A and B, terminating at a central office, and a link circuit C theretofore for interconnecting these lines. It is believed that this invention will be fully understood from a description of the operation of the system shown in the drawing, and it will be so described.

The operator, after being informed by the subscriber of telephone line A connected with cord circuit C (in any desired manner), that connection with line B is desired, inserts calling plug 5 into jack 6 of line B, whereupon relay 7 and cutoff relay 8 operate, and a calling supervisory lamp 9 lights over a circuit from battery through lamp 9, winding of relay 7, sleeve contacts of plug 5 and jack 6, and the winding of cutoff relay 8 to ground. Upon the operation of relay 7, ringing relay 10 operates over a circuit from battery through the winding of relay 10, normal contacts of relay 11 and tripping relay 12, and contact of relay 7 to ground. Relay 10, in operating, opens up the tip and ring strands of the cord circuit, and at the same time connects the tip of the plug 5 through to ground and the ring

thereof with the winding of the tripping relay 12. Relay 10, in operating also causes the operation of start relay 15 over a circuit from battery through brush 16, segment 17 of commutator 18, winding of relay 15, contact 19 thereof, and the middle alternate contact of relay 10 to ground. Relay 15, in operating, serves as a switching device to connect a source of signaling current 25 to line B over a path from the source of signaling current through the right-hand alternate contact of relay 15, winding of tripping relay 12, lower alternate ringing relay 10, ring contacts of the plug 5 and jack 6, over one side of the line, through the call bell and condenser at the substation, back over the other side of the line, tip contacts of the jack 6 and plug 5, upper alternate contact of relay 7, and upper alternate contact of relay 10 to ground. The relay 15, in operating, also completes a locking circuit for itself through its contact 26, this locking circuit including the brush 16 and the segment 17 of the commutator 18. The operation of start relay 15 also completes an operating circuit for motor magnet 30, which may be traced from battery through left-hand alternate contact of relay 15, winding of motor magnet 30, and interrupter 31 to ground. Motor magnet 30 is thereupon intermittently actuated, attracting its armature 32 to cause pawl 33, connected therewith, to engage a tooth of a ratchet wheel 34, secured to shaft 35 upon which the commutator 18 is mounted. The successive energization of motor magnet 30 causes, through the pawl 33 and the ratchet wheel 34, successive one-step advancements of the commutator 18 in the direction indicated by the arrow. When the commutator has rotated a distance equivalent to the length of the segment 17, the brush 16 passes off of segment 17 on to segment 40. As contact 19 is broken between brush 16 and segment 17, the locking circuit of relay 15 is broken, whereupon this relay releases and opens the hereinbefore traced operating circuit for the motor magnet 30. However, when the brush 16 moves off of segment 17, it immediately moves on to segment 40, whereupon a second operating circuit for the motor magnet is substituted for the first. This second cir-

cuit may be traced from battery through brush 16, segment 40 of commutator 18, winding of motor magnet 30 and interrupter 31 to ground. Upon the removal of the receiver from the switchhook by subscriber B, tripping relay 12 is operated, thereupon removing the short circuit of relay 11, which then operates and locks up. The operation of relay 11 short-circuits relay 10, which releases, removing ringing current from the called line, and closing the breaks in the talking strands of the cord circuit. Immediately upon the release of relay 10, supervisory relay 41 is operated to connect a shunt circuit, including resistance 42, about the calling supervisory lamp 9, whereupon this lamp is effaced.

If the called subscriber removes his receiver from the switchhook before the commutator 18 has made a complete revolution, the commutator will continue its movement until the brush has again reached the normal position indicated in the drawing. Since ringing relay 10 is now released, the initial energizing circuit for start relay 15 is open, and the commutator and motor magnet associated therewith remain inactive. If, when the commutator reaches its normal position, ringing relay 10 is still operated, the initial energizing circuit for relay 15 will again be closed, thereby starting the second rotation of the commutator.

From the above, it will be seen that in a system utilizing the present invention, ringing upon the called line starts almost immediately upon the insertion of the calling plug of the cord circuit into the jack of that line. It will furthermore be seen that the present invention provides a comparatively short ringing interval, followed by a comparatively long interval in which ringing current is not connected to the line, and that when once started, the commutator always makes a complete revolution.

45 What is claimed is:

1. A telephone exchange system comprising telephone lines, a link circuit, a source of signaling current, a commutator, an electromagnetic switching device for connecting signaling current to a line and operating under the control of the commutator in response to the connection of the link circuit with a line, and motor mechanism for actuating the commutator started upon the operation of the electromagnetic switching device.

2. A telephone exchange system comprising telephone lines, a link circuit, a source of signaling current, a commutator, an electromagnetic switching device for connecting signaling current to a line, an operating circuit therefor including the commutator, completed in response to the connection of the link circuit with a line, and motor mechanism for actuating the commutator started

upon the operation of the electromagnetic switching device.

3. A telephone exchange system comprising telephone lines, a link circuit, a source of signaling current, a rotatable commutator adapted when started to make a complete revolution, an electromagnetic switching device operating under control of the commutator when the link circuit is connected with a line to connect signaling current therewith and released when the commutator has rotated a predetermined distance, motor mechanism for rotating the commutator, an operating circuit therefor completed upon the operation of the switching device, and a second operating circuit therefor substituted for the first operating circuit when the commutator has rotated the predetermined distance.

4. A telephone exchange system comprising telephone lines, a link circuit, a source of signaling current, a rotatable commutator adapted when started to make a complete revolution, an electromagnetic switching device adapted when operated to connect signaling current to a line, an operating circuit therefor including the commutator established upon the connection of the link circuit with a line and maintained until the commutator has rotated a predetermined distance, motor mechanism for rotating the commutator, an operating circuit for the motor mechanism including a contact of the switching device, and a second operating circuit for the motor mechanism substituted for the first mentioned operating circuit when the commutator has rotated a predetermined distance.

5. A telephone exchange system comprising telephone lines, a link circuit, a source of signaling current, a step-by-step actuated commutator, an electromagnetic switching device for connecting signaling current to a line, an operating circuit therefor including the commutator completed in response to the connection of the link circuit with a line, an intermittently actuated motor magnet for actuating the commutator, and an operating circuit for the motor magnet completed upon the operation of the switching device.

6. A telephone exchange system comprising telephone lines, a link circuit, a source of signaling current, a rotatable commutator adapted when started to make a complete revolution, an electromagnetic switching device adapted when operated to connect signaling current to a line, an operating circuit therefor including the commutator established upon connection of the link circuit with a line and maintained until the commutator has rotated a predetermined distance, an intermittently actuated motor magnet for imparting step-by-step movement to the commutator, and an operating circuit for the

motor magnet established by the operation of the electromagnetic switching mechanism and maintained by the commutator after the rotation thereof for the predetermined distance.

5 7. In a telephone exchange system comprising telephone lines, a link circuit, a source of signaling current, a commutator, an electromagnetic switching device for con-

necting signaling current to the line operating 10 under the control of the commutator, motor mechanism for actuating the commutator, and means controlled by said switching means for starting said motor mechanism into operation.

15 In witness whereof, I hereunto subscribe my name this 20th day of March A. D., 1917.

ROY D. CONWAY.
